UNITED STATES PATENT OFFICE.

RICHARD W. HANNA, OF RICHMOND, CALIFORNIA, ASSIGNOR TO STANDARD OIL COMPANY OF CALIFORNIA, OF SAN FRANCISCO, CALIFORNIA, A CORPORATION OF CALIFORNIA.

PROCESS OF REFINING VISCOUS PETROLEUM OILS.

1,404,389.

Specification of Letters Patent. Patented Jan. 24, 1922.

Application filed January 13, 1920. Serial No. 351,160.

To all whom it may concern:

Be it known that I, RICHARD W. HANNA, a citizen of the United States, residing at Richmond, in the county of Contra Costa and State of California, have invented a new and useful Process of Refining Viscous Petroleum Oils, of which the following is a specification.

My invention relates to an improved process for refining viscous petroleum oils for the manufacture of lubricating oils.

This process is particularly adaptable for refining viscous California petroleum oils, or oils of like chemical composition containing a high percentage of hydrocarbons of the carbocyclic series, for the manufacture of lubricating oils.

My invention relates to a practically continuous process of purifying and refining California petroleum viscous distillates for the manufacture of lubricating oils, in which I remove from said viscous distillates, by means of sulphuric acid and other refining liquids, certain hydrocarbons which contain sulphur in chemical combination, certain hydrocarbons which contain nitrogen in chemical combination, certain asphaltic hydrocarbons, and certain unsaturated hydrocarbons.

An object of my invention is to provide a continuous time saving method of refining.

Another object of my invention is to provide a process for commingling viscous hydrocarbons with sulphuric acid and preventing oxidation which increases with the heat of reaction, thus preserving the color and increasing the quantity of the yields.

Another object of my invention is to extract the heat of reaction produced upon the commingling of viscous hydrocarbons with sulphuric acid, to prevent the reduction of the resultant sludge.

Another object of my invention is to provide a method or process whereby viscous hydrocarbons may be commingled with sulphuric acid or other refining agents, without the use of air agitation, paddles, or similar means.

A further object of my invention is to provide a process of the kind referred to, which will utilize temperature control and the exclusion of air to prevent oxidation products from being formed.

A further object is to provide a continuous means of collecting the products formed by the action of sulphuric acid on viscous hydrocarbons, by the introduction of regulated quantities of water to cause the small particles of sulpho-acids or sludge to coalesce and sludge.

It has heretofore been customary to treat that fraction of oil obtained in the distillation of crude petroleum oil, which fraction is commonly known as lubricating distillate or lubricating reduced distillate, with sulphuric acid, in such quantities and of such strength as may be necessary to obtain the desired color and grade. This treatment is usually carried out in tanks called agitators, where the required amount of sulphuric acid is added and brought into contact with the oil by air agitation. The sulphuric acid reacts on the oil, forming sulpho-acids and other bodies commonly known as sludge, with the liberation of heat.

I have discovered that the liberation of heat during the aforesaid action of the sulphuric acid on the oil, promotes oxidation. Particularly is this so in the presence of air. Such oxidation is accompanied by the formation of petroleum carboxyl-acids, phenolic hydrocarbons and carboxyl-sulpho acids, which are soluble in the oil and act as an emulsifying agent in the neutralizing and washing step hereafter described. I attribute this oxidation partly to the air agitation employed in the aforesaid agitation and partly to the fact that the action of the sulphuric acid on the oil takes place while the products are in a heated condition due to the heat of reaction between the oil and acid. The sulphuric acid reacting on the oil in heated condition is partly reduced to sulphurous acid intensifying the formation of emulsifying or coloring bodies.

My invention provides a continuous conducting away of the main heat of reaction produced in the reaction of the acid on the oil, and the prevention of air coming into contact with the oil under treatment, thus eliminating the formation of emulsifying agents.

My invention further provides for the continuous introduction of a small amount of water (2% to 6% by volume) into the system directly after the acid treatment,

which causes the small particles of sulpho-acids or sludge to coalesce and settle.

With the processes as practiced heretofore it has been customary to treat the oil in 5 tanks, after drawing off the acid sludge or sulpho-acids, with a water solution of caustic soda in sufficient quantity to neutralize all the acids present, after which the oil is washed with hot water to remove all traces 10 of caustic soda and sodium salts. Due to the presence of emulsifying agents produced in such processes as aforesaid, this treating or washing of the oil has been accomplished by a loss of treated oil as high as 15%.

15 My process contemplates a like treating of the oil with a solution of caustic soda after separating the sulpho-acids or sludge. This may be performed in a continuous manner similar to the acid treating process, 20 and owing to the absence of emulsifying agents the loss in treatment is greatly reduced.

In the accompanying drawings:

Figure 1 is a general diagrammatic view 25 of an apparatus in which my invention may be carried out.

Fig. 2 illustrates one form of mixer which may be used for commingling viscous oils with sulphuric acid.

30 Fig. 3 illustrates another form of such mixer.

Fig. 4 illustrates another form of the same.

Fig. 5 illustrates another form of the 35 same.

Fig. 6 illustrates another form of the same.

Fig. 7 illustrates one form of union between the oil line and the acid line.

40 Referring to Fig. 1 of the drawings 1 designates a storage tank for the oil to be treated. A pipe 2 connects the tank 1 to the suction side of a pump 3, which discharges into a pipe 4. The pipe 4 is connected to an orifice meter 5 which records the rate of flow. From the orifice meter 5 the oil to be treated passes into a pipe 6, where it meets the incoming acid from a pipe 20 which is connected to the line 6 45 by means of a T or Y.

50 17 is a tank for acid connected to a pipe 18. The pipe 18 is connected to an orifice meter 19, which latter is connected to the pipe 20 by the Y or T into the line 6.

55 The line 6 is connected to a mixer 7 which is in turn coupled by means of a pipe 8 with a second mixer 9. The mixers 7 and 9 are surrounded by a water jacket 21.

The mixer 9 is connected to a pump 11 60 by means of a pipe 10. The pump 11 discharges into a pipe 13. A water line 12 leads from a source of water and connects with the pipe 13. An orifice meter 22 is positioned on the pipe 12 to determine and 65 regulate the flow of water into the pipe 13.

The pipe 13 is connected to a cooler 14. A pipe 15 connects between the cooler 14 and a settling tank 16.

70 My method may be carried out in this process as follows:

The oil to be treated may range in viscosity from as low as 40 seconds at 100° Fahr. to as high as 250 seconds at 210° Fahr., when taken with the Saybolt viscometer.

75 From tank 1 the oil to be treated enters the suction side of pump 3 by means of pipe 2. The pump 3 discharges through pipe 4 into orifice meter 5 which records the flow of oil. From orifice meter 5 the oil to be treated flows into the line 6 where it is mixed continuously with the required regulated quantity of acid from pipe 20.

80 17 is a tank or blow case, which can be filled with acid by pipe 24, which leads 85 to a source of acid. 23 is a pipe leading to a source of compressed air. 25 is a pipe by means of which the pressure can be released into the air when it is necessary to fill the tank 17 with acid.

85 A pressure of 50 to 150 pounds per square inch absolute is kept on tank 17, which causes the acid to flow through line 18 into orifice meter and regulator 19. Orifice meter 19 is controlled by means of valves so that 90 the flow of acid can be regulated.

95 From the pipe 6, the oil to be treated mixed with the required amount of acid, passes through mixers 7 and 9.

100 The mixers 7 and 9 may be conveniently constructed in any of the forms illustrated in Figs. 2-6 inclusive. In Fig. 2 the mixer comprises a plurality of circular plates 26 which are perforated on alternate half sections as shown at 27. In Fig. 3 the mixer 105 comprises a perforated cap 28. In Fig. 4 the mixer comprises a perforated plate 29 arranged slightly different from that of Fig. 3. In Fig. 5 the mixer comprises a plurality of rectangular plates 30 perforated alternately. In Fig. 6 the mixer comprises a plurality of return bends 31.

110 In the mixers 7 and 9, the oil and acid are commingled. The heat produced by the chemical reaction between the oil and the acid is conducted away as fast as it is liberated by means of cold water which flows through the water jacket 21.

115 From mixer 9 the acid treated oil and acid sludge pass through the pipe 10 into 120 the suction side of pump 11, which discharges into line 13. In line 13, the treated oil mixed with the acid sludge or sulpho-acids produced by the treatment are mixed with a small quantity of water 2% to 6% by volume, by means of line 12, controlled by water meter and regulator 22.

125 This introduction of water into the treated oil and acid sludge causes the small particles of acid sludge to coalesce, so that the 130

- treated oil can be separated in tank 16, the acid sludge forming a lower layer. This introduction of water also is attended by the liberation of heat, which is conducted 5 away by any suitable means, not shown, as the oil passes through the cooler 14. Cooler 14 is connected to a settling tank 16, where the acid sludge settles to the bottom forming a lower layer and is drawn off. 10 The treated oil is then neutralized with a water solution of caustic soda washed with water, and finished by well known methods, or the apparatus here described can be used for this neutralizing and washing steps. 15 I claim:
1. The continuous process of treating viscous petroleum distillate with sulphuric acid which comprises forcing together the oil and acid under pressure in the absence of air in a conduit and conducting away the heat of the reaction from the intermingled oil and acid as generated. 2. The continuous process of treating viscous petroleum distillate with sulphuric acid which comprises forcing together the oil and acid under pressure into a conduit and in the absence of air, and conducting away the heat of the reactions as the same is liberated during the passage of the oil and acid through said conduit. 25 30

Signed at Richmond, California, this 2nd day of January, 1920.

RICHARD W. HANNA.
